COMBINED HEATER AND DISPENSER FOR SHAVING CREAM OR THE LIKE

Gregory F. Fossella, Marblehead, Mass., assignor to Texas Instruments Incorporated, Dallas, Tex., a corporation of Delaware

Filed Mar. 15, 1967, Ser. No. 6,227

Term of patent 14 years

(Cl. D4—3)

FIG. 2

FIG. 1 is a front perspective view of a combined heater and dispenser for shaving cream or the like showing my new design; and

FIG. 2 is a rear perspective view thereof.

I claim:

The ornamental design for a combined heater and dispenser for shaving cream or the like, substantially as shown and described.
